US00D858548S

(12) **United States Design Patent** (10) Patent No.: **US D858,548 S**
 Senger et al. (45) Date of Patent: ** Sep. 3, 2019

(54) **DISPLAY SCREEN WITH GRAPHICAL USER INTERFACE**

(71) Applicant: **INVENTIO AG**, Hergiswil (CH)

(72) Inventors: **Enrico Senger**, Hergiswil (CH); **Tobias Struck**, Berlin (DE)

(73) Assignee: **INVENTIO AG**, Hergiswil (CH)

(**) Term: **15 Years**

(21) Appl. No.: **29/616,987**

(22) Filed: **Sep. 11, 2017**

(30) **Foreign Application Priority Data**

Apr. 13, 2017 (CH) 143187

(51) **LOC (12) Cl.** **14-04**

(52) **U.S. Cl.**

USPC **D14/486**

(58) **Field of Classification Search**

USPC D14/485-495

(57) **CLAIM**

The ornamental design for a display screen with graphical user interface, as shown and described.

DESCRIPTION

The FIGURE is a front view of a display screen with a graphical user interface showing our new design.

The broken line showing of a display screen forms no part of the claimed design.

1 Claim, 1 Drawing Sheet
